UNITED STATES PATENT OFFICE.

HERMAN SCHOENER, OF ST. CLOUD, MINNESOTA.

COMBINED HAND HOE AND SHAVER.

1,253,284.

Specification of Letters Patent.

Patented Jan. 15, 1913.

Application filed August 29, 1917. Serial No. 188,807.

To all whom it may concern:

Be it known that I, HERMAN SCHOENER, a citizen of the United States, residing at St. Cloud, in the county of Stearns, and 5 State of Minnesota, have invented a new and useful Combined Hand Hoe and Shaver, of which the following is a specification.

This invention relates to a combined hand hoe, weeder, and ice shaver, or scraper, one 10 of the objects of the invention being to provide a simple compact device which can be readily adjusted so as to be used as a hoe with the handle extending at any desired angle therefrom, which can be used as a tool 15 for shaving the top soil to cut out weeds, and which can also be used as a means for removing ice from pavements.

With the foregoing and other objects in 20 view, which will appear as the description 25 proceeds, the invention relates in the combination and arrangement of the parts and in the details of construction hereinafter described and claimed, it being understood that changes in the precise embodiment of the 25 invention herein disclosed can be made within the scope of what is claimed, without departing from the spirit of the invention.

In the accompanying drawings the preferred form of the invention has been 30 shown.

In said drawings:—

Figure 1 is a side elevation of the tool arranged for use as a hoe.

Fig. 2 is a side elevation showing the tool 35 adjusted for use as a weeder and, in dotted line as an ice chopper.

Fig. 3 is a front elevation of a structure with the parts in position as shown in Fig. 2.

Fig. 4 is a section on line 4—4 Fig. 1. 40 Referring to the figures by characters of reference 1 designates a handle having a ferrule 2 from which extends a neck 3 terminating in an eye 4. Arranged on one face of this eye is a series of radial teeth 5 and extending through a squared opening 6 in the center of the eye, is a squared portion of a bolt 8. This bolt is extended through an eye 9 provided on one face with a series of radial teeth 10, these teeth being 45 adapted to extend between the teeth 5 as shown in Fig. 3, thus to hold the two eyes against relative rotation. A nut 11 on the bolt is used to bind the eyes 4 and 9 together 50 so as to hold their teeth interfitting.

Extending tangentially from the eye 9 is 55 an arm 12 terminating in a web 13 extending at an angle therefrom and which is formed with or secured to the blade 14 of the device.

As shown in Fig. 1 the eye can be ad- 60 justed angularly relative to the eye 4 thus to bring the blade 14 into position beyond one end of the handle so that it can be em- 65 ployed as an ordinary hoe. If preferred, however, and as shown in full lines in Fig. 35 2, a further adjustment of the line 9 can be made so as to bring the hoe 14 in a plane substantially parallel with the handle at which time the tool can be used as a weeder. Should it be desired to use the device for 70 cutting ice and scraping it off of pavements or like, it is preferred to adjust the blade to the position shown by dotted lines in Fig. 2. When thus positioned the heel portion 15 of 75 the arm 12 comes against the ferrule 2 and holds the blade approximately at 45 degrees to the ferrule, and when the blade 14 is 80 chopped down into the ice the force of the blow is transmitted directly from the blade through the heel portion of arm 12 to the 85 ferrule or sleeve 2 and the arm 12 and the eyes 4 and 9 are thus relieved of the ex- 90 cessive strains to which they would other- 95 wise be subjected during the chopping of ice.

What is claimed is:—

An implement of the class described in- 85 cluding a handle, a ferrule thereon, an eye at one end of the ferrule, an angularly ad- 90 justable eye normally engaging one face of the eye upon the ferrule, means for holding 95 the eyes against relative movement, a tan- 100 gential arm extending from the adjustable eye and having a heel portion, a web ex- 105 tending at an acute angle from said heel por- 110 tion, a blade connected to the web, said 115 arm being adjustable angularly with its eye to bring the heel portion into contact with the ferrule and the blade at an angle of ap- 120 proximately 45 degrees to the ferrule.

In testimony that I claim the foregoing 100 as my own, I have hereto affixed my signature in the presence of two witnesses.

HERMAN SCHOENER.
